UNITED STATES PATENT OFFICE.

JOSEPH HUNTER DICKINSON, OF LARCHMONT, NEW YORK, ASSIGNEE TO THE AEOLIAN COMPANY, A CORPORATION OF CONNECTICUT.

PUPPET-VALVE.

1,285,069.

Specification of Letters Patent. Patented Nov. 19, 1918.

Application filed March 31, 1916, Serial No. 88,042. Renewed September 16, 1918. Serial No. 254,670.

To all whom it may concern:

Be it known that I, JOSEPH HUNTER DICKINSON, a citizen of the United States, residing at Larchmont, in the county of Westchester and State of New York, have invented certain new and useful Improvements in Puppet-Valves, of which the following is a specification.

My present invention relates to an improved valve construction for pneumatically operated automatic musical instruments, including player pianos, etc. The features and advantages of my invention will be apparent to those skilled in the art from an understanding of the following description in connection with the drawings.

In the latter, Figure 1 is a vertical section and side-elevation of parts of a pneumatic piano player embodying my valve construction; Fig. 2 is an enlarged detail of said valve construction; Fig. 3 is a face view on a still larger scale of one of the valve-seat plates; Fig. 4 is an edge view of said plate; Fig. 5 is a perspective view of the plate; and Fig. 6 is a vertical section partly in elevation diagonally through the two valve seats that is, namely, on a line corresponding to 6—6 in Fig. 3.

Describing now the specific devices of the drawings,—1 is the tracker and music-roll box of the instrument, 2 the tracker-board, 3 one of the tracker-tubes, 4 is the valve-board showing the particular pouch 5 to which the tracker tube 3 leads, 6 is the usual cylindrical puppet-valve operated by said pouch. 7 is the striker-pneumatic and 8 the passage controlled by said valve whereby the striker-pneumatic is connected either with the exhaust in chamber 9 through the lower valve-seat 10 or with the atmosphere through the upper valve-seat 11 depending upon the position of the valve 6 as operated by the pouch 5 from the passage of the perforated music-sheet over the tracker-bar, all as well understood in the art. 12 is an endwise reciprocating part pivoted at 13 to the movable board of the striker pneumatic and guided by a hole in the stationary part 14 to act as shown on the wippen 15 to actuate the hammer 16 in well known manner.

My present improvement resides specifically in the upper and lower valve-seats 10 and 11 which may be identical in construction so that the description of one suffices for both. Each preferably is struck up 55 from a plate of sheet metal and has the form best shown in Figs. 3, 4 and 5. Instead of the usual circular opening through the valve-seat, I shape it like a Greek-cross or otherwise give it such other shape, as for 60 example with entrant angles, that the periphery of the opening will be increased and its area reduced. The reduced area means that the suction in chamber 9 does not act so strongly on the valve 6 to hold it on its seat 10 with the result that a relatively small pouch 5 will lift it off its seat. This in turn means that even a small perforation in the music sheet quickly passing over the tracker will let in enough air to lift the pouch and 70 valve to operate the striker-pneumatic. Further that rapidly repeated notes as in a trill will be properly reproduced. The elongated periphery of each valve-seat opening also functions to the same advantageous 75 end because it gives just that much more gate-way for the suction and atmosphere respectively to pass. In short I am enabled to control a large wind-way from a small primary pouch without any secondary and 80 thereby obtain a very quick responsive control of the striker pneumatics from the note-sheet.

Further, so that the atmosphere and suction will have as free access as possible to the 85 active faces of the valve and seat, and to the opening in the latter, I locate said opening in the top of a raised portion 18 of the seat and in addition prefer to surround said opening with a narrow raised rim 19. In 90 this way, the atmosphere or suction as the case may be, is right at the very rim of the valve-seat opening ready to act in full force through it the instant the valve is moved even a slight distance off its seat. To the 95 same end, the portions 20 of the valve-seat plate are depressed to give just as free access of the air to the entrant corners of the opening as to the ends of the slots.

Each plate has holes 21 by which it is 100

secured in position by screws 22. 23 is a narrow strip secured by two of said screws 22 diametrically across each plate. A central hole in each receives and guides one end 5 of the stem of the valve.

What I claim is:—

1. A valve seat for the puppet valve of a pneumatically-operated musical instrument, having its opening formed with entrant 10 angles which give it a relatively large periphery and small area, thereby to increase the gate-way for the rapid communication of the pneumatic tension when the valve is open and to reduce the action of said tension on the valve when closed.
2. A valve seat for the puppet valve of a pneumatically-operated musical instrument, having a many-sided opening giving it a relatively large periphery and small area, 20 thereby to increase the gate-way for the rapid communication of the pneumatic tension when the valve is open and to reduce the action of said tension on the valve when closed.
3. A valve seat for the puppet valve of a pneumatically-operated musical instrument, having its opening serrated, which gives it a relatively large periphery and small area, thereby to increase the gate-way for the 30 rapid communication of the pneumatic tension when the valve is open and to reduce the action of said tension on the valve when closed.
4. A puppet valve seat whose opening 35 comprises a plurality of crossed slots.
5. A valve seat for the puppet valve of a pneumatically-operated musical instrument, the opening in said seat controlled by the valve comprising a slot which gives it a relatively large periphery and small area, 40 thereby to increase the gate-way for the rapid communication of the pneumatic tension when the valve is open and to reduce the action of said tension on the valve when closed.
6. A valve seat for the puppet valve of a pneumatically-operated musical instrument, the opening in said seat controlled by the valve having an increased periphery and a 50 reduced area compared to the periphery and area of a circle circumscribed about said opening, thereby to increase the gate-way for the rapid communication of the pneumatic tension when the valve is open and to reduce the action of said tension on the valve when closed.
7. A valve seat for the puppet valve of a pneumatically-operated musical instrument, the opening in said seat controlled by the 60 valve having a longer periphery and a reduced area compared to the area of a circle circumscribed about said opening, thereby to reduce the action of the pneumatic tension on the valve.

8. A valve seat for the puppet valve of a 65 pneumatically-operated musical instrument, the opening in said seat controlled by the valve having a longer periphery than that of a circle circumscribed about said opening, thereby to increase the gate-way for the 70 rapid communication of the pneumatic tension when the valve is open.

9. A puppet-valve and its seat, the latter having an opening comprising a plurality of crossed slots, said opening having a narrow 75 raised rim to coact with the valve.

10. A valve seat for the puppet valve of a pneumatically-operated musical instrument, the opening in said seat having an increased periphery and a reduced area compared to 80 the periphery and area of a circle circumscribed about said opening, thereby to increase the gate-way for the rapid communication of the pneumatic tension when the valve is open and to reduce the action of said tension on the valve when closed; said opening having a narrow raised rim for co-action 85 with said valve, so as to permit the pneumatic tension to act immediately at said rim.

11. A valve seat for the puppet valve of a pneumatically-operated musical instrument, the opening in said seat having a long periphery and a reduced area compared to 90 the area of a circle circumscribed about said opening, thereby to reduce the pneumatic tension exerted through said opening upon the valve; said opening having a narrow raised rim for co-action with said valve, so as to permit the pneumatic tension to act immediately at said rim.

12. A valve seat for the puppet valve of a pneumatically-operated musical instrument, the opening in said seat having a longer periphery than that of a circle circumscribed 100 about said opening, thereby to increase the gate-way for the rapid communication of the pneumatic tension when the valve is open, said opening having a narrow raised rim for co-action with said valve, so as to 110 permit the pneumatic tension to act immediately at said rim.

13. A puppet-valve and its seat, the latter having a narrow, elongated opening provided with a raised rim to coact with the 11 valve.

14. A puppet-valve seat consisting of a plate having a raised portion whose top contains the valve opening which has a longer periphery than that of a circle circumscribed about it.

15. A puppet-valve seat consisting of a plate having a raised portion whose top contains the valve opening which has a longer periphery than that of a circle circumscribed about it, said opening being surrounded by a narrow raised rim.

16. A puppet-valve and its seat, the latter

consisting of a plate having a raised portion whose top contains the valve opening consisting of a plurality of crossed slots.

17. A puppet-valve and its seat, the latter 5 consisting of a plate having a raised portion whose top contains the valve opening consisting of a plurality of crossed slots, said

opening having a narrow raised rim to coact with the valve.

In testimony whereof I have signed my 10 name to this specification this thirtieth day of March, 1916.

JOSEPH HUNTER DICKINSON.
